SEWING MACHINE

Frederick George Tillett, Eastbourne, England

Application September 20, 1930, Serial No. 483,316
In Great Britain May 7, 1930

12 Claims. (Cl. 112—102)

This invention is for improvements in or relating to sewing machines or an embroidery frame attachment therefor which enables characters such as letters, figures, script and the like 5 to be stitched into a piece of material for example an article of clothing.

Devices of this class usually comprise a design reproducing frame, such as a pantograph, provided with a work holder and a stylus which requires manual manipulation to move it over a master design so as to reproduce the design in stitching in a piece of material or the like carried by the work holder.

The present invention provides various improvements in this class of device which enable the manipulation thereof to be effected with greater rapidity and certainty than has heretofore been possible.

The invention mainly consists in a device of the class described, of the combination of at least one member operable manually to move a piece of fabric in two substantially transverse directions and readily changeable positive guiding means for said member operable to determine the configuration of the path of movement of the said manually controlled member whereby a piece of material arranged under the control of the said member is moved through a path corresponding substantially to the configuration of the guiding means for the purpose specified.

The guiding means may conform to a series of characters so that the apparatus may be used for the purpose of marking articles of clothing and the like with an identifying series of characters or name, for example, as is required in connection with laundries.

In order that the invention may be fully understood, reference is directed to the accompanying drawings, in which:—

40 Figure 1 is a front elevation of an apparatus constructed in accordance with this invention and showing a portion of a sewing machine arranged in conjunction therewith.

45 Figure 2 is a plan view of the apparatus illustrated in Figure 1.

Figure 3 is a section on the line 3—3 of Figure 2.

Figure 4 is a section on the line 4—4 of Figure 2.

50 Figure 5 is a section illustrating a detail on the line 5—5 of Figure 2.

Figure 6 is a plan view of a modified form of guiding means to that shown in Figures 1 to 3.

55 Figure 7 is a section on the line 7—7 of Figure 6.

Figure 8 is a plan view to an enlarged scale of one of the series of guiding characters illustrated in Figures 6 and 7.

Figure 9 is a section on the line 9—9 of Figure 8.

Figure 10 is a plan view of a further modified form of guiding means to that illustrated in Figures 1 to 3.

Figure 11 is a section on the line 11—11 of Figure 10.

Figure 12 is a section on the line 12—12 of Figure 10 but drawn to an enlarged scale.

Figure 13 is a plan view of a modified form of the guiding means illustrated in Figures 10 to 12.

Figure 14 is a section on the line 14—14 of Figure 13, and

Figure 15 is a section on the line 15—15 of Figure 13.

Referring to Figures 1 to 5 of the drawings, a sewing machine 2 mounted upon a work table 1 has a needle 3 which is arranged when operated to sew desired characters into a piece of material or article of clothing by means of an apparatus which is hereinafter described. A movable member 4 in the form of a flat bar is horizontally disposed above the table 1 and is provided with an aperture 5 which is arranged to be located beneath the needle 3. One end of the member 4 has a slot 6 formed therein disposed longitudinally of the said member and the stem of a screw 7 is arranged to extend through the slot 6 so that the head 8 of the screw extends across the upper surface of the member 4 upon either side of the slot 6. The screw 7 at its lower end is screwed into a bush 9 secured within a ball race 10 mounted within a housing 11 which is carried upon the table 1. The arrangement is such that the member 4 is maintained substantially in a horizontal position, but is permitted a slight vertical movement at its free end for a purpose hereinafter described, by virtue of a very slight clearance between the underside of the screw head 8 and the member 4. The slot 6 permits the member 4 to be pivoted around the screw 7 and to be moved in a longitudinal direction relatively thereto.

The member 4 is arranged to extend over a horizontally disposed row of anti-friction balls 12 mounted upon the table 1 and normally to lie in contact therewith. The free end of the member 4 which projects beyond the row of balls 12 is provided with a finger piece 13 which permits the same to be manipulated. A boss 14 is formed in the member 4 adjacent to the finger piece 13. An adjustable spindle 15 is screwed into the boss 14

50 55

and the lower end thereof is adapted to carry a pin 16 in a rigid manner, for example, through the medium of a set screw 14^a, so that the same extends downwardly in a vertical direction. The 5 free end of the pin 16 is arranged to extend into a slot 17 formed in a plate 18 and in the arrangement shown in Figure 2 the slot is in the form of a name in script. A frame member 19 is hinged at 20 to one end 10 of a link 21, the other end of which is hinged at 22 to the member 4. When the frame 19 is in the position indicated in full lines in Figures 1 and 2 an aperture therein is arranged to be located in coincidence with the aperture 5 in the member 4. 15 The member 4 is provided with a rectangular raised rib 23, Figures 2 and 5, which is arranged to extend within a corresponding recess 24 formed in the underside of the frame 19 between two rectangular ribs 25, 26 thereon, Figure 5. The arrangement is such that if a piece of fabric is inserted between the member 4 and the frame 19 and the latter is then pressed into engagement with the fabric and the member 4, the fabric will be stretched over the rectangular rib 26 and will 20 take up the position indicated by the dotted line in Figure 5, so that the fabric extends slightly below the under surface of the member 4. A turnbutton 27 is pivotally mounted upon the upperside of the frame member 19 and is provided 25 with two latches 28 which are arranged to extend into slots 29 formed in two lugs 30 arranged on the member 4, the arrangement being that the turnbutton when in the position illustrated in Figures 1 and 2 firmly clamps the frame 19 into engagement with the member 4. A tension spring 31 is connected between the link 21 and the member 4 so that when the turnbutton is moved to disengage the latches 28 from the slots 29 and the frame member 19 is given an initial upward 30 movement, the spring 31 moves the frame 19 and link 21 into the position indicated in dot and dash lines, Figure 1, and retains them in that position. Any other form of spring may be employed as desired in lieu of the tension spring 31. 35 It is to be observed that a depression of the frame 19 from the raised position causes the free end thereof to contact with the member 4 at a point indicated by the dot and dash lines at A (Figure 1) so that further depression of the frame 19 causes the said frame and the link 21 to be extended into line with one another and the free end of the frame 19 moves beneath the raised needle 3. 40 The operation of the mechanism is as follows:—

A piece of material or article of clothing in which characters are to be stitched is clamped between the frame 19 and the member 4 in the manner described above, and the pin 16 is moved 45 by manipulating the finger piece 13 so as to extend into the slot 17 of the guiding characters. This is permitted by virtue of the slight vertical movement of the free end of the member 4 which is made possible in the manner hereinbefore described. If the sewing machine is now set in operation and the pin 16 is moved through the path formed by the guiding characters by manipulation of the finger piece 13, corresponding characters are stitched into the material located within 50 the aperture 5 by virtue of the accompanying movements of the member 4. The characters stitched by means of the apparatus illustrated are produced on a reduced scale to that of the guiding characters 17 in a direction transverse to 55 the longitudinal axis of the frame member 4, the

stitched characters thus being distorted from the form of the guiding characters; the guiding characters may themselves be distorted to compensate for the distorting action of the member 4.

Arrangements are made to enable the plate 18 in which the guiding characters 17 are formed to be readily changed. To this end the plate 18 is formed of U-shape in cross-section as shown in Figure 1 and is arranged to be placed in position around a supporting block 32 provided with a manipulating knob 33 and to be located thereon between lugs 32^a. The block 32 with a plate 18 in position thereon is arranged to be slid between a pair of guides 34, 35 arranged transversely of the member 4 and which are mounted in a groove 36 formed in the table 1. The guides 34, 35 are arranged respectively to embrace the guide plate 18 and the underside of the block 32 with sufficient friction to retain the guide plate 18 firmly in position. The necessary friction is produced by a turnbutton 37, Figure 2, pivotally mounted upon the table 1 and which is arranged to press upon the upper surface of the guide 34. The guide 34 is provided with an aperture 34^a which is normally disposed above the guiding characters 17 in the plate 18 to enable the pin 16 to be engaged therewith. By rotating the turnbutton 37 out of engagement with the guide 34 the block 32 and the guide plate 18 may be withdrawn from the guides 34, 35 and a fresh guide plate 18 may be placed in position.

A recess 38 is formed in the upperside of the block 32 which is arranged to extend below the slot formed by the guiding characters 17 and enables any fluff which may accumulate in the said slot to be pushed therethrough by the pin 16 and the slot is thereby maintained clear of obstruction.

In order that guiding characters comprising a code number or the like may be used in addition to the script characters illustrated in Figures 1 and 2 and which are provided in a separate mechanism hereinafter described, the guides 34 and 35 are slidably mounted in the groove 36 so that they may be moved in the direction of the arrow a, Figure 2, clear of the free end of the member 4. The guides 34 and 35 are connected together by means of a bolt 39 which is arranged to extend through the said guides and through a slot 40, Figures 2 and 3, formed in the table 1 at the bottom of the groove 36, to ensure that the guides 34, 35 are moved together.

A mechanism which enables any series of guiding characters to be selected is illustrated in Figures 6 to 9 and diagrammatically in Figure 2. In the said figures a framework 41 in which the said mechanism is mounted is arranged to be moved along guides 42 secured to the underside of the table 1 so that the mechanism may be correctly located with respect to the pin 16 carried by the member 4. The mechanism comprises a series of character wheels 43, 44, 45, 46 mounted respectively upon a spindle 47 and nested tubes 48, 49 and 50 arranged concentrically therewith. One end of the spindle 47 is mounted in a bearing 51 in the frame 41 and the tube 50 is similarly mounted in a bearing 52. The spindle 47 and the tubes 48, 49 and 50 are arranged to extend beyond the front edge of the table 1, the inner tubes and the spindle 47 being arranged successively to extend beyond the next outermost tube. Each of the said tubes and the spindle is provided with a hand wheel 53 secured thereto so that a rotation of the hand wheel effects rotation of the corresponding character wheel 43, 44, 45 or 46,

each of which is provided with a series of guiding characters 54 in the form of slots, in the uppermost of which the pin 16 may be arranged to extend. Each of the hand wheels 53 is provided with characters around the periphery thereof corresponding in outline and position to those upon the appropriate character wheel and in order that each of the hand wheels may be readily associated with the correct character wheel corresponding hand wheels and character wheels are coloured in a distinguishing manner.

Each of the hand wheels 53 is provided on one face thereof with a series of notches 55, corresponding in number to the series of characters thereon and are arranged to cooperate with spring controlled detents 56 which are each arranged to locate one of the hand wheels and the corresponding character wheel in any selected position.

Thus it will be observed that by rotation of the hand wheels 53 any selected combination of guiding characters may be moved into the uppermost position upon the character wheels 43 to 46 and the pin 16 may be moved so as to extend through the slots formed by the guiding characters in succession and be guided thereby to effect movements of the member 4 which ensure that corresponding characters are stitched into a piece of material located over the aperture 5 of the member 4.

The slots forming the guiding characters in the character wheels 43 to 46 are arranged to extend completely through the rim of the said wheels so as to prevent the accumulation of fluff in the said slots and where a character is of such a nature that a portion of the rim of the wheel would normally be disconnected from the said rim the said portion is provided with a bridge piece 57, Figures 8 and 9, which connects the central portion of the character to the rim of the wheel. Depressions 58 are formed in the bridge piece 57 upon either side of the central portion of the character as to allow the pin 16 to extend completely through the rim as indicated in Figure 9.

When the mechanism described above is not required for use, it is only necessary to move the same along the guides 42 into the position indicated in dot and dash lines in Figure 2; the guides 34, 35 then being moved into position to enable guide plates 18 hereinbefore described to be used.

A modified form of mechanism to that illustrated in Figures 6 to 9 is illustrated in Figures 10 to 12 in which a series of bars 59 are slidably mounted in a frame 60 which is arranged to engage with the guides 42 in a similar manner to the frame work 41 of the mechanism illustrated in Figures 6 to 9. Each of the bars 59 is provided with a series of slots in the form of guiding characters 62, which may be selectively located beneath an aperture 63 formed in the frame 60 by an appropriate longitudinal movement of the bars 59. Each of the bars 59 is provided with a manipulating knob 64 and a blade spring 65 secured to the frame 60, is arranged to press a detent 61 provided thereon into engagement with the underside of each of the bars 59. The detents 61 are arranged to coact with depressions 61a formed in the underside of the bars 59 so as to locate them in any selected position.

The arrangement is such that when the apparatus is arranged in position upon the table 1 the aperture 63 is located beneath the pin 16 of the member 4 so that the said pin may be moved

into engagement with any of the guiding characters 62 which are aligned below the said aperture. The guiding characters 62 are then utilized to effect the stitching of similar characters to an article of clothing or the like in a manner similar to that described with reference to Figures 6 to 9.

It is to be observed that in lieu of the knobs 64 a series of vertically disposed levers may be pivotally mounted to brackets secured to the frame 60 and the lower end of each lever is operatively connected to one of the bars 59 so that a manipulation of the upper ends of the levers effects the required longitudinal displacement of the said bars.

Referring now to Figures 13 to 15 a mechanism similar to that shown in Figures 10 to 12 is illustrated in which the longitudinal movement of the bars 59 is effected by the rotation of the corresponding series of knobs 66. Each knob 66 is mounted at one end of a spindle 67 which is rotatably mounted in bearings in the frame 60 so as to extend beneath the bars 59. Each spindle 67 is provided with a pinion 68 keyed thereto which is arranged to mesh with and to support a toothed rack 69 provided upon the underside of the corresponding bar 59. The racks 69 are supported at a second point by a guide wheel 70 which is rotatably mounted upon one of the spindles 67. The guide wheels 70 are flanged to prevent the same from moving out of engagement with the corresponding racks.

It will be observed that by rotating the knobs 66 any selected series of guiding characters on the bars 59 may be moved into alignment beneath the aperture 63 in the frame 60.

A pair of clamps 71 are arranged within the frame 60 and located one upon either side of the series of bars 59 and the lower ends of which are secured at 72 to the frame 60. A locking spindle 73 is arranged to extend through holes formed in the clamps 71 and one end of the said spindle is provided with a nut 74 arranged in engagement with the outer face of the adjacent clamp 71, whilst the other end of the spindle 73 is arranged to extend outside the frame 60 and is provided with an operating handle 75. The spindle 73 is provided with a cam 76 which is arranged to coact with an abutment 77 secured to the outer face of the clamp 71 which is disposed remote from the nut 74. The arrangement is such that rotation of the spindle 73 by the handle 75 in one direction causes the cam 76 to move the abutment 77 and the corresponding clamp 71 therewith so as to lock the bars 59 against movement. Rotation of the spindle 73 in the opposite direction causes the cam 76 to release the clamps 71 and permit the bars 59 to be manipulated.

I claim:

1. In a device of the class described, the combination of a manually operable design reproducing frame provided with work holding means, a guiding stylus on said frame, a plurality of members movably mounted upon a support therefor and each provided with a guideway conforming to a desired configuration, and means operable to move any selected member into a predetermined position relatively to said support and render the guideway in said member accessible to said stylus for the purpose specified.

2. In a device of the class described, the combination of a manually operable design reproducing frame provided with work holding means, a guiding stylus on said frame, at least one wheel rotatably mounted upon a support therefor, a plurality of guideways in the form of characters

disposed around the periphery of said wheel and means operable to secure said wheel in any selected position about its axis whereby said stylus may be moved to extend into a selected guideway 5 for the purpose specified.

3. In a device of the class described, the combination of a manually operable design reproducing frame provided with work holding means, a guiding stylus on said frame, at least one bar member slidably mounted in a support therefor, a plurality of guideways conforming to characters formed in said bar, said bar being movable to bring any selected character into a predetermined position relatively to said support in which it is accessible to the said stylus for the purpose specified.

4. In a device of the class described, the combination of a manually operable design reproducing frame provided with work holding means, a guiding stylus on said frame, at least one bar member slidably mounted in a support therefor, a plurality of guideways conforming to characters formed in said bar, said bar being operable so as to move any selected character into a predetermined position in which it is accessible to the said stylus, and means operable to lock said bar in any selected position, for the purpose specified.

5. In a device of the class described, the combination of a manually operable design reproducing frame provided with work holding means, a guiding stylus on said frame, a plurality of guide bars slidably mounted in a support therefor and located in side by side relationship to one another, a plurality of guideways in the form of characters in each of said bars, said bars being operable so as to move any selected character on each thereof into a predetermined position relatively to said support with the selected characters aligned with one another and in which the said characters are accessible to said stylus for the purpose specified.

6. In a device of the class described, the combination of a manually operable design reproducing frame provided with work holding means, a guiding stylus on said frame, at least one bar member slidably mounted in a support therefor, a plurality of guideways conforming to characters formed in said bar, rack and pinion mechanism operatively connected to said bar and operable manually to move the bar and bring any selected character into a predetermined position in which it is accessible to the said stylus for the purpose specified.

7. In a device of the class described, the combination of a manually operable design reproducing frame provided with work holding means, a guiding stylus on said frame, at least one bar member slidably mounted in a support therefor, a plurality of guideways conforming to characters formed in said bar, rack and pinion mechanism operatively connected to said bar and operable manually to move the bar and bring any selected character into a predetermined position in which it is accessible to the said stylus and means operable to lock said bar in any selected position for the purpose specified.

8. In a device of the class described, the combination of a manually operable design reproducing frame provided with work holding means, a guiding stylus on said frame, a plurality of

guide bars slidably mounted in a support therefor and located in side by side relationship to one another, a plurality of guideways in the form of characters in each of said bars, rack and pinion mechanism operatively connected to said bars and operable to move any selected character in each bar into a predetermined position relatively to said support with the selected characters aligned with one another and in which position the said characters are accessible to said stylus for the purpose specified.

9. In a device of the class described, the combination of a frame member operatively connected towards one end thereof by pin and slot mechanism to a support so as to be operable manually to be oscillated about said pin and to be moved longitudinally thereon, a stylus on said member located towards the other end thereof, a work holder carried by said member and located between said support and said stylus, at least one plate provided with a rigid guide surface for said stylus conforming to a desired configuration and a support for said plate having attachment means therefor to enable said plate to be readily changed and to be retained on said support in a fixed position, for the purpose specified.

10. In a device of the class described, the combination of a frame member operatively connected towards one end thereof by pin and slot mechanism to a support so as to be operable manually to be oscillated about said pin and to be moved longitudinally thereon, a stylus on said member located towards the other end thereof, a work holder including a clamping frame located between said support and said stylus, means operable to lock the said frame in a clamping position and means operable automatically to maintain said frame when unclamped in a position spaced away from said member, for the purpose specified.

11. A guide device for an embroidery frame of the class described, which comprises in combination a frame, at least one bar member slidably mounted for lengthwise movement in said frame, a plurality of guideways recessed into said bar in spaced relationship therealong and each conforming in configuration to a character, a frame element disposed over said bar and an aperture in said element so dimensioned that said characters can be exposed therethrough one at a time by lengthwise movement of said bar.

12. A guide device for an embroidery frame of the class described, which comprises in combination a frame, a plurality of bar members slidably mounted for lengthwise movement independently of one another in said frame, said bars being arranged in side by side relationship with one another, a plurality of guideways recessed into each of said bars in spaced relationship therealong on faces thereof disposed in one plane and each guideway conforming in configuration to a character, a frame element covering at least a portion of all said bars, and an aperture in said element extending across all said bars and of a width such that the characters of all said bars can be exposed through the aperture in any combination of any one character from each bar by lengthwise movements of said bars.
